CLAIM

The ornamental design for a cutting board, as shown and described.

DESCRIPTION

FIG. 1 is a first top, front isometric view of a cutting board, showing our new design;

FIG. 2 is a second top, front isometric view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.
